CLAIM

The ornamental design for a contoured vehicle storage enclosure, as shown and described.

DESCRIPTION

FIG. 1 is a top isometric view of a contoured vehicle storage enclosure;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a back view thereof.

The broken lines depict portions of the contoured vehicle storage enclosure that form no part of the claimed design.
